BUTTON LOOP

Application filed June 6, 1930. Serial No. 459,471.

This invention relates to button loops of the type having depending resilient arms the terminals of which are formed for a relative movable association with an attached member providing a seat for the shank of a button within the loop.

The objects of the invention are to provide a two-part expansible button loop of which a contracted portion of one part is expansibly held by an axial strain upon the other part; to provide a two-part button loop of which one part is of rigid structure and the other part is laterally expansible only upon the relative axially yielding movement of the rigid part; and to provide a two-part button loop with integral connections adapting the forced movement of one part to consequentially produce a movement of the other part in the plane of the loop, but at right angles to the forced movement. With these and other objects in view the invention consists in the novel constructions, to be herein-after described or claimed, for carrying out the above stated objects and such other objects as hereinafter may be made to appear.

The character of the invention may be best understood by reference to one illustrative device embodying the novel features herein disclosed and illustrated by the accompanying drawings in which the Figure 1 is an elevation of the contracted loop; the Figure 2 is an elevation of the expanded loop; and the Figure 3 is a plan view of a rigid part, the Figures 4 and 5 being modified structures.

The device, as illustrated, comprises the suspension loop 1, the button-receiving loop 2, the normally contracted throat portion 3, and the button-retaining loop 4, the said loops 1, 2, and 4 being axially associated in that an imaginary vertical center line of one loop is the center line of each of the other loops. The device is made in two parts one of which is of resilient wire of which a middle portion is bent to form the suspension loop 1, the other wire portions depending therefrom to provide the spring side arms 5 and 6 cooperating to provide the button-receiving loop 2 and the normally contracted throat portion 3, the wire adjacent both ends being bent relatively divergent to provide the divergent guides 7

and 8, as illustrated by the Figure 1 and for a purpose to be explained. Stops 9 and 10 are best provided by looping the wire extremities outwardly and backwardly to meet their respective side arms 5 and 6 in spaced relation with the guides 7 and 8, the looping of the extremities adding strength to each guide and also lending a finished appearance to the structure of each wire terminal. The other part of the device is preferably made of sheet metal stamped approximately in the shape illustrated by the Figure 3 and providing the rigid loop structure 11 having the integral sleeves 12 and 13 formed up thereon for a sliding mounted engagement upon the guides 7 and 8, respectively, the lugs 14 being integrally provided by the sleeves 12 and 13 for an extended reach upon the guides 7 and 8 in both longitudinal directions to maintain the rigid loop structure 11 in the plane of the button loop as illustrated by the Figures 1 and 2. In forming the sleeves 12 and 13 the diameters of each are made to lie in the plane of the flat rigid loop structure 11, and hence in the plane of the button loop, so that the complete device may be reversible in the sense that an elevation reverse to that illustrated by the Figure 1 will be identical therewith.

When the shank S of a button rests within the retaining loop 4 and a pulling stress is placed upon the shank, and hence axially of the button loop against the rigid loop structure 11, as illustrated by the Figure 1, the sleeves 12 and 13 are necessarily made to assume positions upon the guides 7 and 8 close to the stops 9 and 10, thereby contracting the arms 5 and 6, and hence the throat portion 3, this contracted condition being maintainable regardless of the spring tension of the arms 5 and 6 so long as the pulling stress is exerted upon the rigid loop structure 11. Therefore, should the tension of the arms 5 and 6 become insufficient to normally maintain a closed throat portion 3, that condition will be maintained by the relatively low position of the rigid loop structure 11 upon the guides 7 and 8. Upon the passing of the shank S through the throat portion 3 the throat is thereby expanded laterally as illustrated by the Figure 2. In order how-

ever that the throat 3 be permitted to so expand the rigid loop structure 11 must bodily yield axially of the button loop upwardly toward the throat 3; for, as the distance between the guides 7 and 8 increases upon the expansion of the throat portion 3, the sleeves 12 and 13 being of relatively fixed dependence must ever associate themselves with correspondingly spaced portions of the divergent guides 7 and 8 upon which they are mounted and therefore slide thereon to their upper positions. Therefore, as the resilient member of the button loop expands laterally, the rigid loop structure 11 must bodily yield axially of the button loop in an upwardly direction and, as a pulling stress is placed axially of the button loop upon the rigid loop structure 11 and bears the structure 11 bodily downward, the arms 5 and 6, and hence the throat portion 3, must as a matter of consequence contract laterally.

The Figure 4 illustrates a fragmentary part of a button loop of identical construction with that of the preferred form above explained excepting that the guides 7 and 8 are provided with stops 8A and 9A of modified form. In place of looping the extremities of the guides 7 and 8 to provide stops, the stops 8A and 9A are provided by upsetting each end of the guides. In this modified form the lower of the lugs 14 are omitted to permit the closer relation between the sleeves and the stops upon the rigid loop structure 11 assuming its lower position upon the guides 7 and 8.

The Figure 5 illustrates a button loop of which the resilient part is identical with that of the preferred form. The rigidly constructed part however is modified in that it is made of wire. In this modified form the wire provides a rigid bar 11A having at either end fixed loops 12A and 13A, each having a portion laterally off-set, one toward the other, in order that the loops 12A and 13A may freely slide over their respective guides 7 and 8 as the rigid structure assumes its upper and lower positions already explained with regard to the preferred rigid loop structure 11.

80 I claim:

1. A two-part expandable button loop providing axially associated loops, one part comprising, in part, a resilient wire button receiving loop having a normally closed throat portion and wire terminals depending therefrom, and the other part comprising a rigid sheet metal button-receiving member, and connection integrally provided by each of the parts, the connections including a pair 85 of relatively divergent guides having stops and provided by the terminals of the resilient wire part, and sleeves rigidly provided by the rigid member for sliding engagement upon the divergent guides for a yielding relative 90 movement of the parts in an axial direction 95 of the associated loops as the throat portion is laterally expanded and contracted.

rection of the associated loops as the throat portion is laterally expanded and contracted.

2. An expandable button loop having axially associated resilient and rigid loop members, the resilient member providing the button loop with an intermediate laterally expandable throat portion normally contracted, and each member being so constructed and both members being so assembled one to the other that both members are thereby maintained in a common plane and, as the throat portion is laterally expanded, the rigid member is thereby bodily moved to an axially upward position relative to the resilient member and, as a downward axial stress is placed upon said rigid member the rigid member is thereby bodily moved to a lower position, relative to the resilient member, such stress cooperating with the resilient tension of the throat portion in maintaining a normally contracted throat portion.

3. An expandable button loop having axially associated resilient and rigid loop members, the resilient member providing the button loop with an intermediate laterally expandable throat portion normally closed, and each member being so constructed and both members being so assembled one to the other that, both members are thereby maintained in a common plane, and, as the throat portion is laterally expanded, the rigid member is thereby bodily moved to an axially upward position relative to the resilient member and, as a downward axial stress is placed upon said rigid member, the rigid member is thereby bodily moved to a lower position, relative to the resilient member, such stress cooperating with the tension of the resilient loop in maintaining a normally closed throat portion.

4. A two-part expandable button loop providing axially associated loops, one part comprising, in part, a resilient wire button-receiving loop having a normally closed throat portion and wire portions depending therefrom, and the other part comprising a rigid sheet metal button-retaining loop member, and connections integrally provided by each of the parts, and adapted to maintain the parts in a common plane, the connections including a pair of relatively divergent guides having stops and provided by the depending wire portions of the resilient wire part, and sleeves rigidly provided by the rigid member for sliding engagement upon the divergent guides for a yielding relative bodily movement of the parts toward and away from one another in axial directions of the associated loops as the throat portion is laterally expanded and contracted.

JESSUP SALISBURY.
